US0D1020231S

(12) **United States Design Patent** (10) **Patent No.:** **US D1,020,231 S**
(45) **Date of Patent:** **** Apr. 2, 2024**

(54) **PILL CASE**

(71) Applicant: **GUANGZHOU WENYI
COMMUNICATION EQUIPMENT
CO., LTD.**, Guangdong (CN)

(72) Inventor: **Youru Feng**, Guangzhou (CN)

(73) Assignee: **GUANGZHOU WENYI
COMMUNICATION EQUIPMENT
CO., LTD.**, Guangzhou (CN)

(**) Term: **15 Years**

(21) Appl. No.: **29/921,307**

(22) Filed: **Dec. 15, 2023**

(51) **LOC (14) Cl.** **03-01**

(52) **U.S. Cl.**
USPC **D3/203.4**

(58) **Field of Classification Search**

Primary Examiner — Steven J Czyz

(57) **CLAIM**

The ornamental design for a pill case, as shown and described.

DESCRIPTION

FIG. 1 is a front view of a pill case showing my new design;
FIG. 2 is a back view thereof;
FIG. 3 is a right side view thereof;
FIG. 4 is a left side view thereof;
FIG. 5 is a top side view thereof;
FIG. 6 is a bottom view thereof;
FIG. 7 is a perspective view thereof;
FIG. 8 is another perspective view thereof;
FIG. 9 is a top perspective view of the pill case, shown in an open state with the lid removed; and,
FIG. 10 is a bottom perspective view thereof.

1 Claim, 10 Drawing Sheets
